WRAPPING MACHINE

Lewis M. Dixon, Bloomfield, N. J., assignor to
Columbia Ribbon and Carbon Manufacturing
Company, Inc., Glen Cove, N. Y.

Application January 20, 1933, Serial No. 652,595

15 Claims. (Cl. 93—2)

My invention relates to the art of packaging merchandise and particularly to a machine for automatically placing wrapping material upon the outside of articles of symmetrical design and uniform size, such as boxes or containers.

5 The objects of the invention are to provide a mechanism whereby wrapping material may be very rapidly applied, and also to produce a wrapping of neat and well finished appearance.

10 Other objects and advantages of the invention will be set forth in part hereinafter and in part will be obvious herefrom, or may be learned by practice with the invention, the same being realized and attained by means of the instrumentalities and combinations pointed out in the

15 appended claims.

These objects are attained by means of the mechanism set forth in diagrammatic form in the accompanying drawings, in which I have shown a preferred embodiment of my invention. It will be obvious to one skilled in the art that many variations may be made in the design and arrangement of this machine without departing from the spirit of the invention, and that many equivalents may be substituted for many of the minor instrumentalities which I show or indicate in these drawings and the following description, and I do not confine myself to those instrumentalities which are herein shown or described.

30 Fig. 1 is an end sectional view of the machine on the line *aa* of Fig. 3.

Fig. 2 is a view partly in section on the line *bb* of Fig. 3.

Fig. 3 is a top view partly in section on the line *cc* of Fig. 1.

Fig. 4 is a detail of a portion of the wrapper feeding device.

Figs. 5 and 6 are details of portions of the driving clutch operating mechanism.

40 Fig. 7 is a detail of the band-severing shear.

Figs. 8, 9 and 10 are details of the package-holding and wrapper-cutting devices at successive stages of operation.

Figs. 11 and 12 are details of the banding material heater and band-severing shear at successive stages of operation.

Figs. 13, 14 and 15 show the package at successive stages of wrapping.

For clarity of description the machine will be 50 considered as being made up of several principal groups of parts and elements which I designate as cam drum, driving mechanism, article-feeder, wrapper-feeder, article-holder, band-applier and severing shear.

The sequence and co-ordination of timing of the

various operations and movements are controlled by means of the cam drum, 1, to which are attached various types of cams, 2, 3, 4, 5, 6, 7 and 9, and a gear segment, 8. These cams and gear engage various levers, rollers and a gear wheel to produce and control the motions of parts as described in detail below.

Power from any suitable source is applied to the pulley, 10, loosely mounted on shaft, 11, upon which the cam drum, 1, is rigidly mounted, under control of the disc clutch, 12, one disc of which is pinned to the shaft 11, and is brought into and out of action by means of the pair of co-operating wedge collars, 13, loosely mounted on shaft, 11, and controlled by means of a foot pedal 14 (see (Fig. 6) attached to shaft, 15, to which is also attached lever arm 16, to which are pin connected rods 17 and 18, by means of which the arms 19 and 20 attached to wedge collars, 13, may be simultaneously moved to expand the wedge combination and so press the driving pulley, 10, against the friction disc clutch, 12, thus transmitting power from the driving pulley to shaft, 11, only while pedal 14 is depressed. The expansion of the wedge collar combination is resisted on one side by the collar 21, and to reduce the friction, ball thrust bearings 22 and 23 are placed on either side of the wedge collar combination, 13. The spring 23a, attached to lever arm 16 and to the frame of the machine returns the mechanism to its former position when pressure on pedal 14 is released.

It will be obvious that power will be transmitted to the shaft, 11, only while the pedal 14 is depressed.

The supply of articles to be wrapped is placed by hand or by any suitable means, such as an automatic feeder, in the inclined trough or chute, 24, which has an opening on one side of its lower end to permit the exit of one article at a time and an opening on the opposite side to admit the plunger, 25, on the end of the plunger rod 26, movable longitudinally in guides 27 and 28. The movement of the plunger rod 26 is actuated in one direction by a spring 29, and is limited in that direction by the collar 30. Its movement in the reverse direction is controlled by lever 114, having on one end roller 115 in contact with collar 116, and on the other end roller 117, which contacts cam 6 on cam drum 1 at each revolution of the drum.

Beside the lower end of the chute, 24, is a pair of spring controlled fingers or tongs, 31, 31, pivoted to the arm 32 by the pivots 33 and drawn inwardly or toward each other by a light spiral spring 34. The arm 32 to which these fingers are

attached is pivotally mounted on the frame of the machine by means of the stud 35, and carries a roller 36 arranged to engage cam 3 on the cam drum 1, whereby the fingers are moved 5 from the position in which they receive the article X to the position in which the article X receives its wrapper, as hereinafter described.

- Two rolls, 37, of the wrapping material are supported on spools 38, loosely carried on shafts 10 39. From the spools the wrapping material 40 leads over two feed rolls 41, mounted on shafts 42 on which are mounted inter-meshing gears 43, one of which is driven by a pulley, 44, by means of a belt 45, which is guided by idlers 48, 15 and passes around a driving pulley, 46, attached to a friction roller, 47, loosely mounted on shaft 49, and confined against longitudinal movement along the shaft by collars 50. The friction roller 47 is intermittently driven by contact with 20 cam 2 on cam drum 1, as will be further described. The strips of wrapper 40 are pressed against the feed rolls 41 by rollers 51, which are mounted on pivoted arms 52, and pressure is maintained by spring 53.
- 25 Slidably mounted in bearings 54 and 55, attached to the frame of the machine below the wrapper feeder are two aligned, opposing spindles, 56 and 57, on the adjacent end of which are cup-shaped article holders, 58 and 59, which are 30 of approximately the size and shape of the article to be wrapped, and which are provided with inserted, compressible material 58a and 59a, or springs to resiliently hold the article without damage. The article holders, 58 and 59 are 35 shaped to fit over the sides of the article so that the article may be pressed a short distance into the cups by compression of the compressible material. This results in the folding of the wrapping material over the edges of the article in 40 the position shown in Fig. 13. Attached to each of spindles 56 and 57 are collars 60 and 61, each provided with lugs 62, and connected by the links 63 and 64, to the pivoted lever 65, which is provided at its lower extremity with a roller 45 66, which contacts with cam 4 on cam drum 1, to impart longitudinal motion to the spindles 56 and 57, as described hereinafter.
- Slidably mounted on spindles 56 and 57 and 50 surrounding article holders, 58 and 59, are two cup-shaped membrane holders, 67 and 68, which also have inserted rings 69 and 70, of resilient compressible material, such as soft rubber, and are each provided with lugs for studs 71 and 72, and connected by links 73 and 74 to pivoted lever 55 75, which is provided at its lower end with a roller 76, which contacts with cam 5 on cam drum 1 to impart longitudinal motion to the cup-shaped membrane holders 67 and 68, as herein-after described.
- 60 Within membrane holder 68 is a circular knife 77, having a serrated cutting edge attached to a plurality of rods 78, passing through openings in the bottom of the cup-shaped membrane holder 68, and rigidly attached to collar, 79, which in 65 turn is slidably mounted on a sleeve 80, which forms a part of membrane holder 68. Attached to collar 79 is a lug, 81, to which is pivoted link 82, connecting with lever 83, which is provided at its opposite end with a roller 84 which 70 engages cam 6 on cam drum 1, to impart motion to the knife 77, as hereinafter described. The spring, 85, serves to return the knife to its former position after having been moved by the cam. The spindles 56 and 57 are provided with 75 sprockets 86 and 87 connected by chains 88 and

89, to sprockets 90 and 91, mounted on shaft 92, upon which shaft is also mounted sprocket 93, cooperating with sprocket 94, by means of chain 95. Sprocket 94 is mounted on a sleeve 96 on shaft 49 and at the opposite end of the sleeve is sprocket 97, which intermittently meshes with gear-toothed segment 8 on cam drum 1 to impart rotary motion to spindles 56 and 57 as hereinafter described.

A roll 98 of banding material is carried on a pin 99 attached to an arm 100 rotatably mounted on shaft 15. Arm 100 supports a band heating unit 101, which may be of the electric resistance type and furnished with current from any convenient source, not shown. A strip of banding material, 98a from the roll 98 leads through the heater 101 and to the inner face of the heater as shown in Fig. 11.

Pivotedly attached to arm 100 is link 102 connecting with lever arm 103, pivoted to bracket 104 on the frame of the machine. Intermediate of the ends of lever arm 103 is mounted roller 105, which contacts with cam 7 on cam drum 1 to impart motion to heater 101 later described. Spring 105a presses roller 105 against cam 25 drum 1.

Rigidly mounted on the frame of the machine is support 106 carrying shears 107, each of the blades of which are pivotally connected by links 108 to opposite ends of arm 109 mounted on shaft 110 operating in sleeve 111. One end of shaft 110 is bent at approximately 90 deg. and carries roller 112, which contacts cam 9 on cam drum to impart motion to the shears as later described. The spring 113 returns the shears to former position after the action of cam 9 has been completed.

Briefly outlined, the above described group or assemblies of elements perform the following functions, each of which will be described in detail herein. The cam drum controls the movements of the working elements of the entire mechanism. The driving mechanism transmits the power for driving the machine and is completely under the control of the operator. All operations are performed automatically and mechanically, that is, without hand labour, and from a single source of power applied at one place to the machine. This makes it convenient to drive the machine by means of one direct-connected motor. The article feeder takes the articles from the feed chute and places them in position to receive the wrapping material. The wrapper feeder places the required quantity of wrapping material on each side of the article in position to be cut to shape and folded over the outer portion of the article. The article holder assembly includes the wrapper cutter and folder. It receives the article from the article-feeder, holds it in position between the wrapping material, while the circular knife cuts out portions of wrapping material, folds the wrapper over the outer portion of the article and revolves the partially wrapped article, while a band of wrapping material is placed around the outer portion of the article and releases the completely wrapped article at the completion of the wrapping process. The band applicator places a strip of heated band material around the outer portion of the article while the article is revolved by the article holder. The band-severing shear cuts off the band of wrapping material leaving a short length of band material unattached to the article to facilitate easy removal of the wrapper.

The band material referred to herein is prefer-

ably a material similar to the wrapping material, but it may be any suitable membranous material which has a coating on one side of an adhesive material, which is non-adhesive when cold, 5 but becomes adhesive when heated to a moderately high temperature.

Or, in place of the heater 101 and band material coated with adhesive which requires heat for its application, I may substitute a moistening 10 device and use an adhesive which becomes sticky when moistened. Or, I may use a device which applies a coating of adhesive to the band material as it passes from the roll 98 to the article being wrapped.

15 The detailed description of the operation of each of these instrumentalities and their coordination each with the other, is as follows:

A supply of wrapping material of suitable width and in the form of rolls, 37, is placed on each of 20 the spools, 38, and a roll 98 of band material is placed on pin 99. Electric current is supplied to heater 101 and power to pulley 10. Since pulley 10 is free to rotate on shaft 11 the machine does not start until lever 14 is depressed, thus 25 operating friction clutch 12 through its instrumentality of wedge collars, 13.

It is assumed that the position of the cam drum 1 is such as it would be at the instant of completion of the wrapping of an article, and 30 that a completely wrapped article has just been released from between the compression heads 58 and 59.

Upon depressing the pedal 14 and thus starting the rotation of the cam drum 1, the cam 2 on the 35 surface of the drum contacts with the friction roller 47, on shaft 49, and rotates pulley 46 and drives pulley 44 by means of belt 45. The rotation of pulley 44 rotates inter-meshing gears 43 and feed rollers 41 against which the strips of 40 wrapping material are pressed by rollers 51 under the action of spring 53, causing wrapping material to be drawn from spools 38 and passed downwardly between compression heads 58 and 59 to the position indicated in Figs. 1 and 2. The cam 45 2 is of such length as to cause just sufficient wrapping material to be drawn into position for use.

Further rotation of cam drum 1 brings cam 3 into contact with roller 36 on arm causing the fingers 31 to move forward and carry the article 50 X to be wrapped into position between article holders, 58 and 59 and between the two strips of 55 wrapping material. As the article X reaches its position, cam 4 on drum 1 moves roller 66 on lever 65, thereby moving spindles 56 and 57 toward each other and bringing article holders, 58 and 59 into contact with the sides of the 60 article and holding the wrapping material against the article, thus supporting the article, whereupon the fingers 31 under control of cam 3 are returned to their former position beside the chute 24. The article X, the wrapping material 40, the 65 article holders, 58 and 59, the membrane holders 67 and 68, and the circular knife 71, are now in the position shown in Fig. 8. Further rotation of the cam drum 1, cam 5, moves roller 76 on lever 75, thereby moving membrane holders 67 and 68 each toward the other, until they surround and enclose the article X and the two strips of wrapping material 40 are held firmly 70 between the rings of resilient compressible material 69 and 70 in the position shown in Fig. 9.

Further rotation of the cam drum 1 brings cam 6 into contact with roller 84 on lever 83 and moves circular knife 71 to shear the wrapping 75 membrane around the article, as shown in Fig. 10.

Further rotation of the cam drum 1 causes cam 4 to move spindles 56 and 57 toward each other compressing resilient rings 58a and 59a, and passing the rims of the cup shaped article holders 58 and 59 over the outside of the article X and 5 folding, crimping or pleating the edges of the wrapping material 40 over the periphery of the article. The article with its surrounding wrap- 10 per is, at this stage of the operation, in the condition indicated in Fig. 13.

Upon further rotation of cam drum 1, cam 6 contacts roller 117 on lever 114, moving plunger rod 26 and forcing an article from feed chute 24 into the space between the fingers 31, where it is held by reason of the pressure caused by the 15 spring 34 until cam 3 again contacts roller 36. Simultaneously with the movements just described, cam 5 acting through lever 75 moves wrapping material holders 67 and 68 away from each other uncovering the circumferential sur- 20 face of the article.

Further rotation of the cam drum 1 brings gear segment 8 on cam drum 1 into mesh with gear 91, rotating sleeve 96 and sprocket 94, which causes the rotation of spindles 56 and 57 through 25 the intermediate agency of chain 95, sprocket 93, shaft 92, sprockets 91 and 90, chains 89 and 88 and sprockets 87 and 86. The number of teeth in the gear segment 8 is such as will cause the spindles 56 and 57 and consequently the partially wrapped 30 article held between article holders, 58 and 59 to rotate one and one eighth revolutions.

Simultaneously with the beginning of this motion, cam 7 on cam drum 1 contacts roller 105 on lever 103 which, through the intermediate 35 agency of link 102 and arm 100, moves the face of heater 101, carrying heated band material 98a into contact with the outer surface of the wrapping on the article. The pressure of the heated band material against the article causes the band 40 material to adhere to the article and the simultaneous rotation of the article draws the strip of band material through the heater. At this stage of the operation, the positions of the shears 107, the article X, the strip of banding material 98a and the heater 101, are as shown in Fig. 11. When one and one eighth revolutions of 45 the article are completed, cam 7 permits the heater to resume its former position out of contact with the article.

Further rotation of cam drum brings cam 9 into contact with roller 112, operating shears 107 through the intermediate agency of bent shaft 110, and links 108 (see Fig. 7), thus severing the banding membrane between the heater 101 55 and the article and leaving a short projecting free portion of the banding material 98a on the article (see Fig. 15). At this stage of the operation, the parts are in the positions shown in Fig. 12.

60 The wrapping is now completed. Further rotation of the cam drum 1 causes cam 4, acting through the intermediate agency of roller 66, lever arm 65 and links 64 and 63 to move spindles 57 and 56 outwardly, releasing the 65 wrapped articles from between article holders, 58 and 59, and allowing articles to fall into any suitable receptacle, not shown in the drawings.

Further rotation of the cam drum repeats in sequence the operations above described. Each 70 complete rotation of the cam drum performs all the operations of wrapping one article.

In some cases operations which are above described as if they were consecutive and distinct in point of time, are in fact somewhat over- 75

lapping, that is, an operation or movement may begin before the completion of the previous movement, so long as there is no interference between the two movements.

- 5 The permissible speed of operation of my machine is very high and is only limited by the accuracy of construction of the machine and perfection of the coordination of the interrelated movements to insure smooth working, freedom 10 from vibration, etc.

I claim:

1. A machine for wrapping articles comprising in combination an article-feeder, a pair of opposed rotatable and axially reciprocatable article-holders, a pair of opposed, reciprocatable wrapper-holders, concentric with and partially enclosing said article-holders, a knife within one of the said wrapper-holders, dual means for providing sources of supply of wrapping material, 20 dual feeders for wrapping material, a band applier, a band-severing shear, a rotatable drum whereon are mounted cams and a gear segment; levers and a gear cooperating with said cams and gear segment adapted to control movements of 25 said feeder, article-holders, wrapper-holders, wrapper-feeders, knife, band applier and band-severing shear.

2. The combination, in a machine for wrapping articles, of means for providing a source of supply of articles, a reciprocating plunger adapted to transfer individual articles from said source of supply to an article feeder, an article-feeder comprising spring controlled fingers mounted on a lever and movable from article-receiving position to article-wrapping position between dual strips of wrapping material, dual means for providing sources of supply of strips of membranous wrapping material, feeding rolls for each of the strips of wrapping material, dual opposed rotatable and axially reciprocatable cup-shaped article-holders, having compressible contact faces adapted to resiliently hold the article between their opposed faces, dual opposed axially reciprocatable cup-shaped wrapper-holders, surrounding and partially enclosing said article-holders, having rings of compressible material within their cups and surrounding said article-holders, a cylindrical knife within one of said wrapper-holders, axially independently reciprocatable to 45 sever the wrapping material, a band applier comprising means for providing a source of supply of banding material and a heater mounted on a lever and movable into and out of contact with the periphery of the article, means for rotating the article while said band applier is in contact therewith, a banding material severing shear, and means including a rotatable drum having cams and a segment of a gear adaptable to move and control the movement of said instrumentalities.

3. A machine for wrapping articles, including in combination means for feeding dual supplies of wrapping material from dual sources of supply, means for placing the article between said supplies of wrapping material, means for holding the article, means for holding said wrapping material, means for cutting said wrapping material to desired shape, means for rotating the article, means for applying an adhesive band around the article 70 while rotating, means for severing the band and means for moving and controlling the movement of each of said means.

4. The combination, in a machine for wrapping articles, of supports for two rolls of strips of membranous wrapping material, feeding rolls for

each of the strips, means for providing a source of supply of articles, means including a reciprocating plunger for transferring one article at a time from the source of supply to an article feeder, an article feeder comprising a pair of spring controlled fingers mounted on a lever and movable from article-receiving position to article-wrapping position between said strips of wrapping material, a pair of opposed rotatable and axially reciprocatable article-holders, a pair of axially reciprocatable, cup - shaped wrapper - holders, which surround and partially enclose said article-holders, having rings of compressible material within their cups, a reciprocatable, cylindrical knife within one of said wrapper-holders, 15 adapted to be reciprocated to sever the wrapping material while said wrapping material is held between the said wrapper-holders, a band applier comprising means for providing a source of supply of banding material, and a heater 20 mounted on a lever and movable into and out of contact with the periphery of the article, means for rotating the article while said band applier is in contact therewith, a banding material severing shear, and means including a rotatable drum, to 25 which are attached cams and a segment of a gear for moving and controlling the movement of all moving parts of the machine.

5. A machine for wrapping articles, including in combination means for feeding dual supplies 30 of wrapping material from dual sources of supply, means for placing the article between said supplies of wrapping material, means for holding the article, means for holding said wrapping material, means for cutting said wrapping material to desired shape, means for rotating the article, means for applying an adhesive band around the article while rotating, means for severing the band, and means including a rotatable drum whereon is mounted cams and a 40 gear segment; levers and a gear cooperating with said cams and gear segment.

6. A machine for wrapping articles, including in combination dual means for providing sources of supply of strips of wrapping material, dual 45 feeding rolls for said strips, an article feeder movable into and out of a position between said strips, dual opposed rotatable and axially reciprocatable cup-shaped article-holders, having compressible contact faces adapted to resiliently hold the article between their opposed faces, dual opposed axially reciprocatable cup-shaped wrapper-holders, surrounding and partially enclosing said article-holders, a cylindrical knife within one of said wrapper holders axially independently reciprocatable to sever the wrapping material, a band applier comprising means for providing a source of supply of banding material and a heater movable into and out of contact with the periphery of the article, a banding material severing shear, a rotatable drum having cams and a segment of a gear, levers and a gear cooperating with said cams and gear segment adapted to move and control the movement of said instrumentalities.

7. The combination in a machine for wrapping articles, of dual means for providing sources of supply of wrapping material, dual means for feeding two strips of wrapping material into position for use, means for positioning the article between said strips of wrapping material, means for holding the article between said strips of wrapping material, means for cutting portions of predetermined pattern from said strips of wrapping material, means for folding peripheral parts of

said cut portions over the edges of the article, and means for applying an adhesive band of wrapping material to the outer surface of said folded portions.

- 5 8. The combination, in a machine for wrapping articles, of supports for two rolls of strips of membranous wrapping material, feeding rolls for each of the strips, an article feeder comprising a pair of spring controlled fingers mounted on 10 a movable lever, two opposed rotatable and axially reciprocatable cup-shaped article holders, two opposed axially reciprocatable wrapper holders, surrounding, partially enclosing said article holders, and axially concentric therewith, a band 15 applier comprising a source of supply of banding material and a heater movable into and out of contact with the article being wrapped.
9. In a machine for wrapping articles, a holder for the article, comprising a pair of opposed 20 rotatable and axially reciprocatable cupped compression heads, each cup having a filler of compressible material, said cups being formed to fit over the edges of the article when interposed there-between.
- 25 10. In a machine for wrapping articles, a device for holding the article during the application of the wrapper, comprising dual opposed rotatable and longitudinally reciprocatable cup-shaped compression heads, having recesses in adjacent faces thereof conforming to the periphery of the article, a cushion of resilient yielding material within said recesses and means for controlling the longitudinal and rotational movement of said heads.
- 30 11. In a machine for wrapping articles, a device for holding the article during the application of the wrapper, comprising dual opposed rotatable and longitudinally reciprocatable, cup-shaped compression heads, having recesses in 35 adjacent faces thereof conforming to the periphery of the article, a cushion of resilient yielding material within said recesses and means including a lever and rotating cam adapted to control the longitudinal movement of said heads, and 40 means including a rotating intermittent drive adapted to control the rotational movement of said heads.
- 45 12. The combination in a machine for wrap-

ping articles of an article holder as described in claim 10, with a pair of opposed cup-shaped wrapper holders, concentric with and surrounding partially enclosing said compression heads and longitudinally movable with respect thereto, having rings of resilient compressible material within said cups and projecting beyond the rims thereof, and means for controlling the longitudinal movement of said holders.

13. In a machine for wrapping articles a device 10 for holding the article as described in claim 10, in combination with a pair of opposed cup-shaped wrapper holders concentric with and surrounding and partially enclosing said compression heads and longitudinally movable with respect thereto, 15 compressible rings within said cups and projecting beyond the rims thereof, and means including a lever and rotating cam adapted to control the longitudinal movement of said holders.

14. The combination in a machine for wrapping articles, of an article holder as described in claim 10, with a pair of opposed cup-shaped wrapper holders concentric with, surrounding and partially enclosing said compression heads and longitudinally movable with respect thereto, having 20 resilient compressible material within said cups and projecting beyond the rims thereof, means for controlling the longitudinal movement of said 25 holders, a knife slidably mounted within one of said holders and longitudinally movable with respect thereto, and means adapted to control the movement of said knife.

15. The combination in a machine for wrapping articles, of an article holder as described in claim 10, with a pair of opposed cup-shaped 35 wrapper holders concentric with, surrounding and partially enclosing said compression heads and longitudinally movable with respect thereto, having resilient compressible material within said cups and projecting beyond the rims thereof, 40 means for controlling the longitudinal movement of said holders, a knife slidably mounted within one of said holders and longitudinally movable with respect thereto, and means including a lever and rotatable cam adapted to control the 45 movement of said knife.

LEWIS M. DIXON.
